UNITED STATES PATENT OFFICE.

CASPER RIESE, OF BERLIN, PRUSSIA, GERMANY.

GAITER CLASP OR FASTENING.

SPECIFICATION forming part of Letters Patent No. 230,498, dated July 27, 1880.

Application filed May 31, 1880. (Model.) Patented in Germany April 13, 1880, in France January 23, 1880, in Belgium December 15, 1879, and in Italy January 30, 1880.

To all whom it may concern:

Be it known that I, CASPER RIESE, of Berlin, Kingdom of Prussia, German Empire, have invented a new and Improved Gaiter 5 Clasp or Fastening, of which the following is a specification.

The object of my invention is to provide a new and improved legging which fits closely to the foot and ankle and can be opened or 10 closed very easily.

In the accompanying drawings, Figure 1 is a side view of my improved legging. Fig. 2 is a side view of a legging of a slightly different shape. Fig. 3 is a plan view of my improved spring-clasp for leggings. Fig. 4 is a longitudinal sectional view of the same. Fig. 15 5 is a side view of the same.

Similar letters of reference indicate corresponding parts.

20 The legging A, made of cloth, leather, or any other suitable material, is provided with a strip, B, of some elastic material or fabric, which may be arranged on either or both sides of the opening of the legging, and extends 25 from the top to the bottom. The opening of the legging is closed by means of a series of spring-clasps, C, which are arranged on one side of the opening, whereas a series of eyes, into which the studs D of the clasps C pass, 30 are arranged in corresponding positions on the other side.

The clasps C consist of a cap, E, of metal, having any suitable design, which cap is piv-

oted to two ears, F, of the base-plate G of the clasp. A projection, H, at the rear of the cap 35 E presses onto a spring-plate, J, attached to the base-plate G by the lower end of stud D. The caps E are first raised, the legging is drawn tightly, so as to fit well, and the studs D are passed into the corresponding eyes on 40 the other side of the opening, and then the caps E are lowered, the spring J preventing the same from opening by accident, and thus the legging is effectually closed. The elastic bands B permit the legging to be stretched, so that 45 it can be used with heavy or light pantaloons and shoes, and the spring-clasps C cannot be opened by the tension of the said elastic bands.

Having thus described my invention, I claim as new and desire to secure by Letters Patent—

The spring-clasp C for leggings, constructed substantially as herein shown and described, and consisting of a cap pivoted on a base-plate, provided with a lower spring-plate acting upon 55 the cap, and with a central stud which is adapted to pass into eyes on the opposite side of the opening of the legging, as set forth.

In testimony whereof I have hereunto set my name in the presence of two subscribing 60 witnesses.

CASPER RIESE.
